(57) **CLAIM**

The ornamental design for a telescopic drying rack, as shown and described.

DESCRIPTION

FIG. 1 is a perspective view of a telescopic drying rack showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is a perspective view of the telescopic drying rack in an expanded state;

FIG. 10 is an enlarged view of the encircled portion in FIG. 1; and,

FIG. 11 is an enlarged view of the encircled portion in FIG. 2.

The equal-length broken lines depict portions of the telescopic drying rack that form no part of the claimed design. The dash-dot lines in FIG. 1, FIG. 2, FIG. 10 and FIG. 11 illustrate the boundaries of the enlarged view indicators and form no part of the claimed design.
